UNITED STATES PATENT OFFICE.

CHARLES H. HALL, OF NEW YORK, N. Y.

IMPROVEMENT IN STEAM AND WATER GAGES FOR STEAM-BOILERS.

Specification forming part of Letters Patent No. 129,948, dated July 30, 1872.

Specification describing a new and Improved Water and Steam Gage, invented by CHARLES H. HALL, of New York city, in the State of New York.

The importance of knowing correctly the level of the water in a steam-boiler has been long recognized. This invention is intended to indicate the true level very correctly, and to show this effect not only in the immediate vicinity, but at a distant point, as in the counting-room of a manufactory or in the cabin of a steam-ship. It will indicate at a different level from the boiler. It allows of being mounted considerably above or an indefinite distance below the level of the boiler. The same instrument, while thus reliably indicating the water-level, also indicates the amount of steam-pressure.

The following is a description of what I consider the best means of carrying out the invention.

The accompanying drawing forms a part of this specification, and represents the gage as applied to a steam-boiler, the gage being in elevation and the boiler in section.

A is a fixed frame-work of wood or metal, and B is a bent glass tube mounted in the position of an inverted U. The two legs of this siphon-shaped tube I will denote, respectively, by B¹ B². The lower end of each is socketed in a metal connection provided with a cock, which connects it, by means of pipes b¹ b², (only portions of which are represented,) with a steam-boiler, M. The mode of connection of these pipes with the boiler is important, and, in connection with certain precautions taken in retaining a proper quantity of air in the gage at the commencement, insures a reliable performance of the apparatus, so that the level of the water in the two legs of the glass tube may indicate both the pressure of the steam and the level of the water. The pipe b¹ connects the base of the leg B¹ with the boiler at or a little above the highest point which the water-level in the boiler is ever expected to attain. This may be described as being at or a little above the level of the ordinary upper gage-cock. The other pipe b² connects from the lower end of the leg B² to a point below that to which the water-level in the boiler is ever expected to sink. The point of junction of the pipe b¹ with the boiler being an impor-

tant feature in the apparatus, I will designate it by a distinctive letter, X.

There may be many means of starting the apparatus in the right condition. I will describe one of the simplest. The cocks D¹ D² being three-way cocks, they are first turned into such position as to discharge from their respective pipes b¹ b² into the atmosphere. Under these conditions the pipe b¹ fills with steam and the pipe b² fills with water. Both cocks are now turned, so that all communication is closed, and the pipe b¹ fills with water produced by the condensation of the steam therein, fresh steam naturally flowing in to supply the place of that which has been condensed until the whole is filled up to the level of its junction with the boiler. Now both cocks D¹ D² are cautiously opened, and the water from both pipes, acted on by the pressure from the boiler, compresses the air in the bent tube B, and causes the water to rise in both legs B¹ B². The air yields by its elasticity, and increases its tension as it is compressed until its tension just equals that in the boiler, assuming the gage to be mounted at the level of the boiler, or a little above or below that pressure, according as the gage is mounted above or below the level of the boiler. Here all motion ceases, and the level of the water in the two legs of the gage, taken conjointly, indicates correctly the pressure in the boiler.

If the water-level in the boiler is up to the point X there will not only be the same steam-pressure felt on each pipe b¹ b², and consequently in each leg B¹ B² of the glass tube, but there will be the same water-pressure in each, and consequently the level of the water in the two legs of the glass gage will exactly coincide with each other; but when the water-level in the boiler gets below the point X there will be correspondingly less water-pressure on the pipe b², and consequently a correspondingly less pressure in the leg B² of the gage. The slightest difference in the pressure in the two legs of the gage is manifested in the corresponding difference of the level of the water therein, because the upper ends of the two legs are freely connected by the bent pipe B. The air, therefore, changes its position from one leg to the other, as required, and the difference in the level of the water in the two

legs, $B^1 B^2$, of the gage is always exactly equal to the depth to which the water-level in the boiler has sunk below the point of connection of the pipe b^1 . The central tube E is a straight glass tube closed at the top, and tightly socketed in the metal connection G at the bottom. When the cock H is open there is a free communication between the two legs of the main gage, before described, and any difference of pressure which may obtain therein at the moment will become equalized. It follows that the cock H must be very tight, and must be open only when it is desired to induce this equalization. Under ordinary conditions the cock H is closed and the main gauge $B B^1 B^2$ operates as above described, while the additional glass tube E serves as an additional gage properly graduated to indicate the press-

ure of the steam alone. It will indicate the pressure as it exists in the leg B^2 . The additional tube E and its graduations avoid the necessity for graduating the legs $B^1 B^2$, and avoid the inconvenience caused by the changes of level in the two legs.

I claim as my invention—

The gage-tube E, with the cross-connection G and cock H, in combination with the gage $B B^1 B^2$ and the connections $b^1 b^2$, as specified.

In testimony whereof I have hereunto set my hand this 22d day of June, 1872, in the presence of two subscribing witnesses.

C. H. HALL.
